UNITED STATES PATENT OFFICE.

SHERIDAN L. HATFIELD, OF READING, MASSACHUSETTS.

COMPOUND ENGINE.

SPECIFICATION forming part of Letters Patent No. 318,898, dated May 26, 1885.

Application filed June 30, 1884. (No model.)

To all whom it may concern:

Be it known that I, SHERIDAN L. HATFIELD, of Reading, in the county of Middlesex and State of Massachusetts, have invented certain 5 new and useful Improvements in Compound Engines, of which the following is a full, clear, and exact description.

This invention relates to a compound rotary steam-engine; and it consists of the construction and arrangement of a revolving steam-chest provided with radial steam-passages and exhaust-passages, in combination with a series of steam-piston cylinders connected to gear-wheels for operation, all substantially as hereinafter fully described.

In the accompanying plate of drawings, Figure 1 represents in cross-section a compound rotary steam-engine constructed according to this invention; Fig. 2, a partial section and 20 partial side view, and Fig. 3 a sectional view in detail.

In the drawings, A represents a cylindrical casing or cylinder having closed ends B. Extending radially from the sides of the casing 25 A are three steam-cylinders, C, D, and E, equidistant from each other and on the same horizontal plane. Each of these steam-cylinders C D E has a piston-head, F, arranged to move back and forth in its chamber G, the 30 piston-head connecting by a pitman-rod, H, with a pin, a, in the side of a disk or plate, J, on a shaft, b, arranged to rotate in suitable bearings, each of which shafts b carries a gear-wheel, K, that engages with a large gear-wheel, L, on a shaft, M, arranged to rotate parallel with the shafts b, and turning in a bearing, d, in the casing A, and by its other end in any suitable support.

The end f of the shaft M extends through 40 the side and into the chamber N of the casing A, and is secured to the side k of a cylindrical steam-chest, P, located in the casing A, its periphery g just fitting within the interior periphery, h, of the casing A.

A shaft, Q, attached to the side l of the steam-chest P, extends therefrom through the wall m of the cylinder A in the same axial line as the shaft M, and is arranged to turn in a bearing, n, of said wall m. The steam-chest is narrower than the cylinder A, so that a space is 50 left each side thereof, as shown more particu-

larly in Fig. 2. The steam-chest P also has a central chamber, R, from which extend outward in radial and slightly-curved directions passages T, opening to the outside surface or 55 periphery, g, of the steam-chest, and diminishing in area in cross-section from the central chamber outwardly.

The casing A has an opening, S, in its periphery opposite to each steam-cylinder, forming 60 a communication therewith.

The shaft Q is hollow, having a chamber, U, which communicates with the central chamber, R, of the steam-chest, and in the operation of the engine steam is let into the chamber R 65 through the shaft Q from any suitable supply, which then passes through the radial passages T and out at the outer end, q, of the one that is in communication with one of the steam-cylinders C, D, or E, which causes its piston-head F to move back, revolving its gear-wheel K, and through it the large gear-wheel L, which turns the shaft M, and thus the steam-chest 70 within the casing A, and the other gear-wheels.

The three cylinders C D E are so arranged 75 in connection with the size of the opening S in the casing that some one of the radial passages is in connection with one of the steam-cylinders C D E at all times, and also so that just before the one radial passage T which is in 80 communication with its opening S with its corresponding steam-cylinder passes by such opening in the rotation of the steam-chest, the second radial passage from it will have formed communication with the steam-cylinder at 85 which it may be, and so on one after the other during the operation of the engine, so that there shall be a constant pressure upon the shaft for the proper working of the engine, and thus the gear-wheel L and its shaft M, with 90 a constant supply of steam to the steam-chest, will be constantly and evenly revolved, and by proper connection, &c., properly operate mechanism connected therewith.

The crank-pins a on the disks are so arranged 95 in relation to each other—that is, on the “thirds,” so called—that the dead-center is entirely obviated.

After the outer end of each steam-passage T has passed the opening S in the cylinder 100 there comes to such opening S a passage or opening, V, in the periphery g of the steam-

chest, which communicates by a passage, *r*, through the side wall and opening into the chamber *N*. These passages *V* are for the exhaust, and in the revolution of the disk *J* by its gear *K* the piston-head is caused to travel backward in the steam-cylinder, forcing the steam out through the exhaust-passage *V*, then in communication therewith into the chamber *N*, out through a pipe, *t*, and by the time all the steam is out of the cylinder the piston-head will be near the inner end in position to be acted upon by the steam passing from the next radial passage, which in the continued revolution of the steam-chest has come into proper position.

The steam-cylinders are all arranged to be supported upon a frame in any suitable manner, and also the shafts *M b* of the gear-wheels are arranged to turn in suitable bearings in such support, all as is usual, and needing no particular description herein.

In Fig. 3 the steam enters through a pipe, *W*, into the chamber *N*, and passes into the radial passages *T* through separate openings *v* in the side of the steam-chest, which can be used, if desired, in lieu of through the shaft.

The exhaust is by similar passages, *w*, opening to the other side of the steam-chest, as shown in the drawings, and exhausting into the chamber *N* and out at the pipe *t*.

Having thus described my invention, what I claim, and desire to secure by Letters Patent, is—

The combination, with a steam - chest arranged to revolve in a suitable steam cylinder or casing, and provided with steam radial and exhaust passages, and having communication with a steam-supply, of steam piston cylinders having communication with said steam-cylinder, the piston-heads of which piston-cylinders are connected to gear-wheels arranged to engage with a gear-wheel attached to the shaft of said steam-chest for operation, all substantially as and for the purpose specified.

In testimony whereof I have hereunto set my hand in the presence of two subscribing witnesses.

SHERIDAN L. HATFIELD.
